United States Patent Office.

DAVID HARGER, OF DES MOINES, IOWA, ASSIGNOR TO HIMSELF, D. H. YOUNG, AND A. S. VORSE.

Letters Patent No. 74,083, dated February 4, 1868.

IMPROVED COMPOSITION FOR ROOFING.

The Schedule referred to in these Letters Patent and making part of the same.

TO ALL WHOM IT MAY CONCERN:

Be it known that I, DAVID HARGER, of Des Moines, in the county of Polk, and in the State of Iowa, have invented certain new and useful Improvements in Compound for Roofing; and do hereby declare that the following is a full, clear and exact description thereof.

My invention consists in the use of the within-named ingredients, compounded and used substantially as follows:

Coal-tar, three (3) parts, (not boiled); sand, three (3) parts; quicklime, three (3) parts; sulphate of zinc, one-ninentieth ($\frac{1}{19}$) part; flour of sulphur, one-ninentieth ($\frac{1}{19}$) part; thoroughly mixed into a homogeneous mass, thereby making a compound or concrete mixture for roofing and other purposes.

This mixture is designed to be used on plain, batten, old shingle, felt, paper, or metallic roofs, and to make the same fire-proof it is only necessary to sift a coat of dry sand over the surface of the mixture after laying on the same. It is also a superior and cheap article to put on fences, posts, and out-buildings, to preserve the wood, in lieu of paint. Any shade of color may be given to the mixture by simply adding any coloring-matter.

I do not wish to confine myself to any specific proportions of the within-named ingredients.

Having thus fully described my invention, what I claim as new, and desire to secure by Letters Patent, is—
A roofing-composition, composed of unboiled coal-tar, sand, quicklime, sulphate of zinc, and flour of sulphur, all combined and used substantially as and for the purposes set forth.

In testimony that I claim the foregoing, I have hereunto set my hand, this 13th day of November, 1867.

DAVID HARGER.
